UNITED STATES PATENT OFFICE.

CLAES RYDEN, OF PROVIDENCE, RHODE ISLAND, ASSIGNOR TO UNIVERSAL WINDING COMPANY, OF PORTLAND, MAINE, A CORPORATION OF MAINE.

WINDING-MACHINE.

1,171,544.

Specification of Letters Patent. Patented Feb. 15, 1916.

Application filed September 30, 1912. Serial No. 723,156.

To all whom it may concern:

Be it known that I, CLAES RYDEN, a citizen of the United States, residing at Providence, in the county of Providence and State 5 of Rhode Island, have invented certain new and useful Improvements in Winding-Machines, of which the following is a specification.

My invention relates to improvements in 10 winding machines for winding yarn and thread or the like into cops or bobbins.

The object of my improvement is to provide a machine for producing cops or bobbins wound with cylindrical layers in such 15 manner as to form them with tapered or conical ends, thereby making them more stable and less liable to be damaged from the coils becoming displaced or falling down over the ends. To accomplish this result 20 my improved mechanism provides for automatically and progressively shortening the extent of traverse of the thread-guide, which disposes the coils of yarn, throughout the complete winding of the cop, thereby 25 gradually reducing the length of the layers of winding as the cop increases in diameter.

The invention is fully set forth in the following specification, illustrated by the accompanying drawings, in which:

30 Figure 1 is a front elevation of my improved winding machine, with the driving-pulley and clutch-devices shown in section on a vertical plane extending through the axis of the winding-spindle; Fig. 2, an end elevation, part sectional on the line X—X of Fig. 1; Figs. 3, 4, 5 and 6, detail views of the improved transverse-mechanism of the machine; Figs. 7 and 8, detail views of the stopping-mechanism of the machine.

40 My new machine is similar in general structure to that shown and described in my previous application for patent, Serial No. 706,063, filed June 26, 1912. It is designed to be built in "gangs" or series of any suitable number of heads or units and, as all 45 of the heads are alike, only one will be here described. Likewise, as the opposite ends of each head are identical in arrangement and operation, the elements at one end only 50 are herein shown and described.

Referring first to Fig. 1, the main frame A of the machine consists of the base a and two side-members or uprights a', a', joined at the top by an arch or bridge-piece a².

55 The side-members a', a' are formed with

bearings a³, a³ for the horizontally arranged winding-spindle B and hubs a⁴, a⁴ for the parallel cross-rod C which is secured therein by suitable means such, for instance, as the set-screw c. Extending outward at each 60 side of the frame A and supported by a suitable standard A' arranged in back of the base a is an arm a⁵ terminating in a bearing a⁶ for the rock-shaft D, see also Fig. 2. Unlike the machine of the application 65 previously referred to, the present one has two rock-shafts, one on either side of the frame and both extending horizontally below and at right-angles to the winding-spindle. It will be understood that the 70 rock-shafts extend the whole length of the bed or table which supports the several heads or units and are connected to a cam or other suitable device for imparting an oscillating movement to them. The rock- 75 shafts D carry arms D' for transmitting motion to the reciprocating thread-guides which are traversed axially of the winding-spindles, as more fully explained herein-after.

In my present machine the winding-spindle B is made in two separate alining sections b and b', joined in the center by a stepped bearing which is preferably constructed with a reduced portion b² of the 85 section b projecting into an axial bore b³ in the end of the section b'. This provides that the cop-drivers at either end of the machine can be started and stopped independently of each other so that when the rotation of the 90 cop at one end is arrested, for piecing-up or other cause, it will not necessitate the stopping of the cop at the other end. Both sections of the spindle B are rotated from a common driving-pulley E which is connected thereto by independent clutch-devices 95 F and F'. The pulley E is driven from a driving belt, not here shown, which is preferably arranged to connect the pulleys of all the winding heads to a common source of 100 power at the end of the bed or table. As both of the clutch-devices F and F' are the same, only one need be described. Referring to Fig. 1, the pulley E is formed with beveled clutch faces e, e' at its opposite sides. 105 The clutch-member F is mounted to slide on a bushing f, mounted on the spindle-section b, and has a tapered periphery f' adapted to engage the face e of the pulley E. One end of the bushing f abuts the end of the hub of 110

the pulley E and the opposite end bears against the face of a collar f^2 which, in turn, abuts the end of the bearing a^3 . The arrangement is the same on the opposite side 5 of the pulley E, and in this way the pulley is held from side play on the spindle B. The collar f^2 is formed with a radially extending key f^3 which engages a slot f^4 in the end of the bushing f, see Fig. 8, and a set-screw f^5 10 secures the collar to the spindle B so that both the collar and bushing rotate therewith. The key f^3 is also adapted to engage a radial slot f^6 in the rear face of the clutch-member F so that when the latter is connected to the 15 pulley E it drives the spindle-section b, see Figs. 1 and 8. The periphery of the collar f^2 is scored with an annular groove f^7 into which is sprung the end coil of a helical, wire spring f^8 and the opposite end of the 20 spring bears against the clutch-member F to normally hold it in engagement with the pulley E. The clutch-member F is formed with a tapered flange f^9 adapted to be engaged by a lever G, see Fig. 8, to withdraw 25 it from the pulley E to arrest the rotation of the spindle-section b, as more fully explained hereinafter. The clutch-member F is operated in the same manner to control 30 the rotation of the opposite spindle-section b'.

The outer end of the spindle B projects a short distance beyond the side of the frame A and is formed with a reduced portion b^4 35 adapted to fit the bore of the cop-tube or "quill" x on which the cop is wound. Usually, wooden quills are employed for this purpose and their ends are slotted at x', see Fig. 2, to receive a radially disposed spline or key b^5 which is carried in the end of the 40 spindle B. The key b^5 serves to drive the quill x and the outer end of the latter is supported on the end of a "live" spindle h mounted in a sleeve h' in the bearing H. The sleeve h' is arranged to slide in the bearing 45 H and is operated by a spring to allow its retraction during the insertion of the quill, but these parts are not here shown in detail as their arrangement is well known in the art. The bearing H surmounts an arm h² 50 which extends from a hub h³ secured on a rod H', the latter projecting from the side of the frame A, see Figs. 1 and 2.

Secured in an ear a⁷, projecting from the side of the upright a' of the frame A, see 55 Fig. 2, is a rod I which I term the traverse-rod. Its outer end is supported by an arm C' reaching up from the rod C to which it is secured by the set-screws c². Mounted to slide on the traverse-rod I is a sleeve j, 60 see Fig. 3, on which is swiveled the thread-guide-holder J carrying the thread-guide k, the latter formed with a thread-notch k' for receiving the thread or yarn and guiding it on to the quill x. The thread-guide k is 65 adapted to swing outward, away from the

axis of the winding-spindle, as the yarn is built up on the quill x, and the upper edge of the guide is maintained in contact with the cop throughout the winding by the weighted traverse-frame L, see Fig. 2. The 70 traverse-frame L is arranged substantially the same as that described in my previous application, before referred to, with its legs l pivoted on the rod I and its back l' bearing against the rear face of the guide-holder J 75 so that the weights l² act to press the guide against the surface of the cop. The yarn y leads down from above through an eye m at the end of an end-stop-lever M, thence over a thread-bail m', and through the notch k' in the guide k.

The end-stop-lever M is secured to a rod N pivoted in bearings l³ on the back of the traverse-frame L and is supported in an upright position, as illustrated in Fig. 2, by 85 the tension of the yarn y. The rod N is formed at its inner end with a crank-arm n, the end of which engages an arcuate slot o⁴ in the curved end of a lever O. The lever O is pivoted on the side of the frame A and 90 has a forwardly extending portion o formed with an ear o' to which is secured one end of a helical spring o². The opposite end of the spring o² is fastened to a lug a⁸ on the frame A and the tendency of the spring is to 95 tilt the forward end of the lever O upward to depress its rear end. Normally, the crank-arm n on the rod N maintains the lever O in the position illustrated in Fig. 2, when the end-stop-lever M is held upright 100 by the tension on the yarn; but when the yarn breaks or is exhausted it will allow the end-stop-lever to tilt backward and this permits the lever O to rock under the influence of the spring o². The tilting of the lever O 105 acts to cause the operation of the stopping-mechanism of the machine to arrest the rotation of the winding-spindle as now explained.

The forward end of the lever O is provided with a triangular opening o³ in which the end of a wire lever p is adapted to play. The lever p is pivoted at the end of an arm P' which is secured to a rod P by a set-screw p'. The rod P is supported by an elbow-portion p² of the arm P' which reaches inward and is secured to the rod H' and by a second arm p³, also secured to the rod H' at its opposite end, see Fig. 1. The rod H' extends through both sides of the frame A and is secured fixedly therein by the set-screws h⁴, h⁴. The rod P is adapted to swing about the axis of the rod H' and is operated manually by a handle P², see Fig. 1, formed by bending the end of the rod at right-angles to its main portion. Secured to the inner end of the rod P by the set-screw g is the clutch-lever G, the movement of the rod acting through this lever to withdraw the clutch-member F from the pulley E, as pre- 130

viously described. Slightly apart from the lever G is a detent-lever S secured on the rod P by a set-screw s. Referring to Fig. 2, the upper end of the lever S is formed with a shoulder s' adapted to engage an opposite shoulder s² on the end of a second detent-lever S'. The lever S' is pivoted on a bearing s³ extending from a lug a⁹ at the top of the frame A, see Fig. 1, and arranged in a pocket a¹⁰ surrounding the bearing is a coiled spring s⁴ adapted to swing the lever in the direction indicated by the arrow 2, Fig. 2: The tendency of the spring s⁴ is normally to maintain the detent-shoulders s' and s² locked together during the operation of the machine; but when the rod P is moved bodily in the direction indicated by the arrow 3, Fig. 2, the detent-shoulders will be released and the face s⁵ of the lever S' bearing against the face s⁶ of the lever S will cause the latter to move the rod P still farther in the same direction. This action serves to carry the tapered end of the clutch-lever G into engagement with the corresponding tapered flange f⁹ of the clutch-member F to withdraw the latter from the pulley E. It is called to attention that during this operation the end of the lever S' does not ride clear off from the end of the lever S, but, on the contrary, the two levers remain in such relation that their shoulders may be readily engaged again through manual operation of the handle P².

Referring to Fig. 1, it will be observed that the wire lever p straddles the arm P' and is formed with an upper arm p⁴, see Fig. 2, which reaches in below the winding-spindle B. Secured to the spindle B opposite the arm p⁴ is a knock-off wheel b⁶ formed with ratchet-teeth or spurs b⁷ on its periphery. The spindle B rotates in the direction indicated by the arrow 4, see Fig. 2, and when the lever p is thrown up into the position here illustrated the end of the arm p⁴ will be engaged by one of the spurs b⁷ to force the arm P' outward and swing the rod P to actuate the clutch-operating lever G. The lever p also has a guard-arm p⁵ which comes into contact with the under side of the wheel b⁶ to prevent the arm p⁴ from being thrown up above the wheel. The lever p is operated to engage its arm p⁴ with the knock-off wheel b⁶ by the tilting movement of the lever O which engages its end through the slot or opening o⁸. It is also adapted to be operated by means connected with the traverse-controlling mechanism hereinafter explained and for this reason the stopping devices have been described in detail.

Mounted on the cross-rod C, outside of the frame A and secured by the set-screws t², t² are two inverted T-shaped members T, T' which support a pair of vertically extending rods t, t'. Mounted to slide up

and down on the rods t, t' is a frame U, preferably formed of sheet-metal with legs u, u having ears u', u' bent over at right-angles and bored to receive the rods, see Figs. 2 and 3. At the upper corners of the frame U are two ears u², u², curled over to surround the rods t, t' and serving to maintain the frame in a vertical position. At the top of the frame U are two uprights u³, u³ formed with double ears u⁴, u⁴ bored to receive a horizontal rod u⁵ which is held in position by the set-screws u⁶, u⁶. Mounted rotatably on the rod u⁵ between the uprights u³, u³ is a pressure-roll U' arranged directly under the cop-quill x and adapted to bear on its periphery so that as the layers of yarn are built up on the quill the growth in diameter of the cop will force the frame downward on the rods t, t'. 85

Extending from the outer side of the frame U is an arm u⁷ to which is pivoted at u⁸ a dogging-lever u⁹. The inner edge of the dog u⁹ is formed with an eccentric cam-face u¹⁰ adapted to impinge on the side of the rod t. The dog u⁹ is released by a finger-piece u¹¹, and a stop u¹² bent out from its lower edge is adapted to engage the under side of the arm u⁷ to limit the upward movement of its dogging end. 90 Normally, the weight of the inner end of the dog tends to frictionally engage it with the rod t so that the frame U is restrained from upward movement while being free to slide downward on the rods t, t'. This 100 prevents the roll U' from vibrating or jumping up and down under the effect of irregularities on the periphery of the cop. 95

Mounted on the opposite side of the frame U is a stop-finger V, preferably formed of sheet-metal and secured in position by a screw v reaching through a vertical slot v', see Figs. 2 and 3. An ear v² on the finger engages a second slot v³ in the frame to prevent it from turning on the screw v. 105 The finger V reaches out at right-angles to the frame U, as shown most clearly in Fig. 2, and is adapted to engage the downwardly-extending arm v⁴ of a lever V', see also Fig. 3. The lever V' is pivoted at v⁵ 110 on a lug p⁶ extending rearwardly from the arm P', see Fig. 7, and has an upwardly extending arm v⁶ bent at right-angles at v⁷ and adapted to engage the end of the lever p, as shown in Figs. 2 and 3. Referring to Fig. 3, the edge of the arm v⁴ of the lever V' is formed with a curved cam-face v⁸ and as the frame U slides down on the rods t, t' the finger V rides over this face and tilts the lever V' to elevate its right-angled portion v⁷. This action raises the lever p to carry its end into engagement with the knock-off wheel b⁶ and thereby cause the operation of the clutch-releasing devices as previously explained. The stop-finger V 115 120 125 130 135

can be adjusted up and down on the frame U by sliding its screw v in the slot v' and this determines the size of the cop being wound. That is to say, the finger V is set 5 according to the size of cop desired and when the winding reaches the predetermined diameter the frame U will have been forced down far enough to cause the finger to trip the lever V' and stop the machine.

10 The improved traverse-mechanism of the machine consists of the following-described instrumentalities: Referring to Figs. 1 and 2, the rocker-arm D' which imparts reciprocation to the thread-guide k is secured to one end of a crescent-shaped block d, by means of screws d', d', the block d being adapted to fit the top of the rocker-shaft D and fastened thereto by a bolt d'. At the opposite end of the block d is fastened 20 a second arm D², held by the screws d³, d³, which reaches up adjacent the traverse-rod I. The thread-guide-holder J is pivoted on the sleeve j by means of its two legs j', j' held in place by wire rings j², j² sprung into peripheral grooves on the sleeve, see Fig. 3. The legs j', j' straddle a member J', also pivoted on the sleeve j, and having a depending arm j³ formed with a slot j⁴, see Fig. 4. The member J' is preferably 25 constructed of sheet-metal, bent at its top to surround the sleeve j and extending downward in two parallel sides j⁵, j⁵, which form the arm j³, see Fig. 2. The sleeve j and its depending arm j³ constitute the 30 traverse slide for reciprocating the thread-guide k. The sides j⁵, j⁵ of the arm j³ straddle the arm D² which is also formed with a slot d⁴.

35 Referring to Fig. 5, which is an enlarged 40 sectional view of the arms D² and j³, taken on the line Z—Z of Fig. 3, the slot j⁴ in the arm j³ is part-spherical in cross-section to adapt it to inclose a ball w which also fits the slot d⁴ in the arm D². The ball w slides 45 on a rod W which is formed with an enlarged portion w' pivoted on a pin w² extending through two ears d⁵, d⁵ at the top of the arm D', see Fig. 2. This arrangement provides for connecting the arm D² 50 and member J' to move together to impart reciprocation to the latter, while the ball-and-socket joint allows the rod W to rock on its pivot to slide the ball w up and down in the slots in the arms j³ and D². Adapted 55 to slide on the rod W between the ball w and pivot w² is a roll w³ formed with an annular, concave groove w⁴, see Fig. 6. The lower edge w¹³ of the frame U is formed as 60 an arc, substantially concentric with the axis of the rocker-shaft D when the frame U is in its uppermost position, and this edge engages the groove w⁴ of the roll w³. At the rear of the pivot w² the rod W is 65 provided with a series of holes w⁵ into which the end of a coil of spring z may be hooked.

The opposite end of the spring is secured to an ear d⁶ bent out from the arm D' adjacent its lower end. The spring z tends to maintain the rod W in a substantially horizontal position with the ball w at the upper 70 end of the slot d⁴ in the arm D². It also acts to resist the downward movement of the frame U on the rods t, t' and serves to maintain the roll U' bearing against the surface of the cop. The amount of pressure of the 75 roll on the cop can be regulated by adjusting the end of the spring in the holes w⁵ to vary the leverage of the rod W. At the commencement of the winding the pressure-roll U' is in its uppermost position, bearing 80 against the cop-quill x, as illustrated in Fig. 3, and the ball w is at the upper end of the slot d⁴ in the arm D² so that the maximum extent of traverse is imparted to the thread-guide k. As the winding continues the 85 growth of the cop forces the roll U' downward, away from the axis of the winding-spindle, and the frame U, bearing on the roll w³, tilts the rod W downwardly as shown in Fig. 2. This carries the ball w downward in 90 the grooves d⁴ of the arm D², so that the operative length of the arm is shortened, and hence the extent of traverse of the thread-guide is reduced.

The operation of the complete machine is 95 as follows: Assuming that the machine is at rest, the quill x is placed in position by mounting its ends on the live-spindle h and spindle-section b with the spline b⁵ engaging the slot x'. The yarn y is drawn down 100 from the source of supply, generally placed above the machine, but not here shown, led through the eye m on the end-stop-lever M, and thence over the thread-bail m' to the quill x, to which the end is secured. The 105 dogging-lever w⁰ on the frame U is now released to allow the pressure-roll U' to be carried up by the action of the spring z to bear against the quill x. As in the machine 110 of my previous application, before referred to, the thread-guide k reciprocates constantly; that is to say, it is not stopped during the arrest of rotation of the winding-spindle. When the spindle is stopped, however, the thread-bail m' is raised automatically 115 and the yarn is lifted out of the notch k' in the thread-guide k so that it is not reciprocated in relation to the quill. After the traverse-frame L has been adjusted to bring the guide k against the surface of the quill x the handle P² is moved to swing the rod P in the direction opposite to that indicated by the arrow 3, Fig. 2. This releases the clutch-lever G from the clutch-member F and allows the latter to be moved into engagement with the pulley E to rotate the spindle-section b and, thereby, the cop-quill x. The detent-shoulders s' and s² on the levers S and S' are, in the meantime, carried 120 into engagement to maintain the lever G 125 into engagement to maintain the lever G 130

away from the clutch-member F and these parts are held in the position illustrated in Fig. 2 during the winding of the cop. As the winding-spindle starts to rotate the 5 thread-bail m' is moved to release the yarn, as described in my application before referred to, and the thread-guide automatically picks it up and reciprocates it along the quill x , depositing it thereon in helical 10 coils which form the cylindrical layers of the cop.

As the layers of yarn build up on the quill x the pressure-roll U' is forced downward to slide the frame U down on the rods 15 t and t' . As the arms D' and D² are oscillated back and forth by the rocker-shaft D the roll w³ slides along the lower, arcuate edge u^{13} of the frame U. Now, as the frame moves downward its pressure on the roll w³ 20 will tilt one end of the rod W downward, against the action of the spring z on its opposite end, and the ball w will slide gradually downward in the slot d⁴ of the arm D². This action alters the point of connection of 25 the arm D² with the arm j³ of the traverse-slide; that is to say, the operative length of the arm D² is gradually shortened so that the extent of traverse imparted to the thread-guide becomes less and less. 30 Referring to Fig. 1, the dot-and-dash lines Y represent the outline of the cop and it will be seen that, whereas the first layer extends substantially the whole length of the quill x, subsequent layers become shorter 35 and shorter as the winding proceeds, so that the ends of the cop assume a conical form. I have shown the machine arranged to produce a cop with its outer layer approximately two-thirds the length of its inner 40 one and this provides a substantial taper at the ends of the cop. These proportions can be varied somewhat, however, by the adjustment of certain elements of the mechanism as now explained: By releasing the set-screws t² and swinging the members T and T' about the rod C the position of the frame U in relation to the pivot of the rod W can be changed and this will alter the ratio of 45 movement between the pressure-roll U' and the ball w. For instance, if the frame U is swung to the left, as viewed in Fig. 2, its point of bearing on the rod W will be carried farther away from the pivot-point of the rod, and hence the movement of the 50 pressure-roll outward from the axis of the cop will impart less movement to the ball w. This will result in a lesser change in the operative length of the arm D² and, therefore, the shortening of the traverse of the 55 thread-guide is more gradual so that the cop will be wound with its ends having less taper. With the ordinary materials a slight taper at the ends of the cop is sufficient to prevent the coils from slipping and becoming 60 misplaced; but for winding linen, silk

or other hard-twisted, slippery threads the maximum taper is advisable. Heretofore, it has been found almost impossible to wind hard, firm cops of these materials by building up the layers with square ends. The 70 constrictive force of the outer layers of winding will invariably displace the end coils and cause the ends of the cop to become "bulged" or malformed so that the thread cannot be unwound freely, and even if the 75 winding operation, itself, is successful, such forms of cops do not retain their shape, and therefore do not deliver freely from the shuttle. The end coils are much more liable to slip off from a square-ended cop and in 80 such event they become caught on the quill or snarled and tangled so that much of the material is often wasted in unwinding it.

My new machine produces a cop which is 85 much more stable and free from the disadvantages noted and provides a marked improvement in the art.

The mechanism of the machine is simple and direct-acting, positive in its control of the traverse of the thread-guide and exceptionally easy to operate.

Various modifications might be made in the form and arrangement of the parts of my new device without departing from the spirit or scope of the invention.

Therefore, without limiting myself to the exact construction shown and described, what I claim is:—

1. In a winding machine, the combination with the winding-spindle, of a thread guide 100 adapted to be traversed with a straight-line movement maintained constantly parallel with the axis of the winding spindle, a separate oscillating arm to reciprocate the guide, pressure-means independent of the guide 105 adapted to bear on the winding to be moved through the growth in diameter of the cop, and means operated by the movement of said pressure-means to vary the effect of the oscillating arm to progressively shorten the 110 traverse of the thread-guide throughout the winding of the cop.

2. In a winding machine, the combination with the winding-spindle, of a thread-guide 115 adapted to be traversed with a straight-line movement maintained constantly parallel with the axis of the winding-spindle, a separate oscillating arm for reciprocating the guide, independent pressure-means bearing on the winding to be moved away from the 120 axis of the cop by the growth in diameter of the latter, and means operated by said pressure-means to shorten the range of action of the guide-reciprocating arm to gradually reduce the extent of traverse of the thread-guide from start to finish of the cop.

3. In a winding machine, the combination with the winding-spindle, of a thread-guide 125 adapted to be traversed with a straight-line movement maintained constantly parallel 130

with the axis of the winding-spindle, a separate oscillating arm for reciprocating the guide, means to connect the guide with the arm, independent pressure-means adapted to bear on the winding to be moved through the growth in diameter of the cop, and means operated by said pressure-means to shift the point of connection of the guide on the oscillating arm to cause a gradual shortening of the traverse of the guide throughout the winding.

4. In a winding machine, the combination with the winding-spindle, of a thread-guide adapted to be traversed with a straight-line movement maintained constantly parallel with the axis of the winding-spindle, a separate oscillating arm for reciprocating the guide, means to connect the guide with the arm, independent pressure-means adapted to 20 of the guide along the arm, a pressure-roll adapted to bear on the winding, and means operated by the movement of said pressure-roll as the cop increases in diameter to cause the shifting-means to move the point of connection of the guide toward the axis of the arm to gradually shorten the length of the layers of winding.

5. In a winding machine, the combination with the winding-spindle, of a thread-guide, 30 means for reciprocating the guide, with a straight-line movement maintained constantly parallel with the axis of the winding-spindle, a frame movable away from the axis of the winding-spindle, a pressure-roll 35 mounted on said frame and adapted to bear on the cop to move the frame, and means operated by the movement of the frame to gradually shorten the extent of traverse of the thread-guide as the cop increases in 40 diameter.

6. In a winding machine, the combination with the winding-spindle, of a thread-guide, means to reciprocate the guide, with a straight-line movement maintained constantly parallel with the axis of the winding-spindle, a frame mounted on bearings to adapt it to slide downward away from the axis of the cop, a pressure-roll mounted on 45 said frame and adapted to bear on the winding to move the frame during the growth of the cop, and means operated by the movement of the frame to progressively shorten the extent of traverse of the thread-guide throughout the winding.

55 7. In a winding machine, the combination with the winding-spindle, of a thread-guide, a separate oscillating arm for reciprocating the guide, with a straight-line movement maintained constantly parallel with the axis 60 of the winding-spindle, a frame, a pressure-roll supported on said frame to bear on the winding, and means actuated by the movement of the frame as the roll is forced away from the axis of the cop to vary the operative effect of the oscillating arm and pro-

gressively shorten the traverse of the thread-guide from start to finish of the winding.

8. In a winding machine, the combination with the winding-spindle, of a thread-guide, a separate oscillating arm for reciprocating the guide, with a straight-line movement maintained constantly parallel with the axis of the winding-spindle, means to connect the guide with the arm, a pressure-roll adapted to bear on the winding, and means operated by the movement of the pressure-roll away from the axis of the cop to shift the connecting-means toward the axis of the arm to gradually shorten the traverse of the guide throughout the winding.

9. In a winding machine, the combination with the winding-spindle, of a thread-guide, a separate oscillating arm for reciprocating the guide, with a straight-line movement maintained constantly parallel with the axis of the winding-spindle, means connected with the guide and slidable on the arm to vary the operative length of the latter, a pressure-roll adapted to bear on the winding to be moved outward from the axis of the cop, and means operated by the movement of the pressure-roll to slide the connecting-means on the arm to progressively shorten the traverse of the thread-guide throughout the winding.

10. In a winding machine, the combination with the winding-spindle and thread-guide, of an oscillating arm formed with a longitudinal slot, an arm connected with the thread-guide and formed with two sides straddling the first arm and with a slot registering with the slot therein, a ball-member fitted to slide in the slots and retained thereby, and means operated by the growth in diameter of the cop to slide the ball in the slots to alter the operative effect of the oscillating arm and shorten the traverse of the thread-guide.

11. In a winding machine, the combination with the winding-spindle, of a traverse-rod, arranged parallel therewith, a thread-guide mounted to slide on the traverse-rod, an arm extending downward from the thread-guide, an oscillating arm adjacent the thread-guide arm, means connecting said arms and slidable longitudinally thereon, and means operated by the growth in diameter of the cop to slide the connecting-means to progressively shorten the traverse of the thread-guide throughout the winding.

12. In a winding machine, the combination with the winding-spindle, of a traverse-rod arranged parallel therewith, a sleeve slidable on said rod, a thread-guide hinged on the sleeve, a slotted arm extending downward from said sleeve, an oscillating arm formed with a slot arranged opposite to the slot in the first arm, means connecting said arms and slidable in the slots, and means

to slide said connecting-means during the building of the cop to gradually shorten the traverse of the thread-guide.

13. In a winding machine, the combination with the winding-spindle, of a traverse-rod arranged parallel therewith, a thread-guide mounted to slide on the rod, a downwardly-extending arm connected with the guide and having two parallel side-portions 10 formed with opposite longitudinal slots, an oscillating arm extending upward between the side-portions of the first arm and formed with a slot, a ball inclosed by said arms and adapted to slide in the slots and means 15 to slide said ball to vary the extent of reciprocation imparted to the guide by the oscillating arm.

14. In a winding machine, the combination with the winding-spindle and thread-guide, of an arm connected with the guide, a rock-shaft, two parallel rocker-arms connected with the rock-shaft and oscillated thereby, a rod pivoted on one of the rocker-arms and engaging the other with the guide-arm, and means to tilt said rod on its pivot 20 to vary the point of connection of said arms in relation to the axis of the rock-shaft.

15. In a winding machine, the combination with the winding-spindle, of a reciprocating thread-guide, a slotted arm connected 30 with said guide, two parallel rocker-arms, means to oscillate the rocker-arms, a rod pivoted on one of the rocker-arms and extending through a slot in the other arm to engage the slot in the guide-arm, and means 35 to tilt said rod on its pivot to vary the operative length of the rocker-arm in its connection with the guide-arm.

16. In a winding machine, the combination with the winding-spindle, of a reciprocating thread-guide, an arm connected with said guide, a pair of oscillating rocker-arms, means to oscillate said rocker-arms, means hinged on one of the rocker-arms and 45 arranged to connect the other arm with the guide-arm, and means to operate said connecting-means to vary the point of connection of the rocker-arm with the guide-arm in relation to the axis of oscillation of the former.

17. In a winding machine, the combina-

tion with the winding-spindle, of a reciprocating thread-guide, an arm connected with said guide, a pair of oscillating rocker-arms, means to oscillate the rocker-arms, a member 55 connecting the guide-arm to one of the rocker-arms and adapted to slide toward and away from the axis of the latter, and means mounted on the other rocker-arm and engaging the connecting-member to slide the latter to vary the extent of reciprocation 60 imparted to the thread-guide.

18. In a winding machine, the combination with the winding-spindle, of a reciprocating thread-guide, a slotted arm connected 65 to said guide, a pair of oscillating rocker-arms with one of said arms formed with a slot, means to oscillate the rocker-arms, a member connecting the guide-arm with the slotted rocker-arm and adapted to slide in 70 their slots, and a rod hinged on the other rocker-arm and extending through the connecting-member to slide it in the slots.

19. In a winding machine, the combination with the winding-spindle, of a reciprocating thread-guide, a pair of oscillating rocker-arms, a member hinged on one of the rocker-arms and connecting the other arm with the thread-guide, and a frame movable 75 away from the axis of the winding-spindle 80 with the growth in diameter of the cop and arranged to tilt the hinged member to shift the point of connection of the guide on the rocker-arm.

20. In a winding machine, the combination with the winding-spindle, of a reciprocating thread-guide, a pair of oscillating rocker-arms, means connected to the thread-guide and slideable on one of the rocker-arms, a rod hinged on the other rocker-arm 90 and engaging the connecting-means to slide the latter, and a frame movable away from the axis of the winding-spindle with the growth in diameter of the cop and arranged to tilt the hinged member to shorten the operative length of the rocker-arm.

In testimony whereof I affix my signature in presence of two witnesses.

CLAES RYDEN.
